Primary Examiner — Vy N Koenig

CLAIM

The ornamental design for a detachable selfie stick tripod, as shown and described.

DESCRIPTION

FIG. 1 is a perspective view of a detachable selfie stick tripod showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the detachable selfie stick tripod;

FIG. 10 is a perspective view of the detachable selfie stick tripod where the detachable selfie stick tripod is in a configuration of use;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 2;

FIG. 14 is an enlarged view of portion 14 shown in FIG. 2;

FIG. 15 is an enlarged view of portion 15 shown in FIG. 2;

FIG. 16 is an enlarged top plan view of the detachable selfie stick tripod; and,

FIG. 17 is an enlarged bottom plan view the detachable selfie stick tripod.

The broken lines in the drawings depict portions of the detachable selfie stick tripod that form no part of the claimed design.
